Patented July 1, 1975

235,605

DOMESTIC BUILT-IN COOKTOP HAVING SMOOTH
COOKING SURFACE AND TOUCH CONTROL
PANEL

David D. Shelley, Romeo, Mich., assignor to General
Motors Corporation, Detroit, Mich.

Filed May 3, 1973, Ser. No. 356,768

Term of patent 14 years

Int. Cl. D7—02

U.S. Cl. D7—121

Fig.1

Fig.2

FIG. 1 is a perspective view of a domestic built-in cooktop having a smooth cooking surface and touch control panel shown mounted in a cabinet which is shown in broken lines for illustrative purposes only and forms no part of the claimed design.

FIG. 2 is a longitudinal sectional view taken along lines 2-2 of FIG. 1 looking in the direction of the arrows; and shown fragmentarily for ease of illustration;

FIG. 3 is a top plan view of the cooktop with the central portion and one corner shown broken away for ease of illustration.

I claim:

The ornamental design for a domestic built-in cooktop having smooth cooking surface and touch control panel, as shown and described.
